UNITED STATES PATENT OFFICE.

PATRICK ALPHONSUS MARTIN, OF BIRMINGHAM, ENGLAND.

DESIGN FOR A GOLF-BALL.

49,905.

Specification for Design.

Patented Nov. 14, 1916.

Application filed June 27, 1916. Serial No. 106,269. Term of patent 7 years.

To all whom it may concern:

Be it known that I, PATRICK ALPHONSUS MARTIN, a subject of the King of Great Britain, residing at Granville street, Birmingham, England, have invented a new, original, and ornamental Design for Golf-Balls, of which the following is a specification, reference being had to the accompanying drawing, forming part thereof.

The figure is an elevational view of a golf ball showing my new design.

Copies of this patent may be obtained for five cents each, by addressing the "Commissioner of Patents, Washington, D. C."

What I claim as new and desire to secure by Letters Patent is:—

The ornamental design for a golf ball, as shown.

In testimony whereof I have hereunto set my hand in presence of two subscribing witnesses.

PATRICK ALPHONSUS MARTIN.
